BALL-TYPE LIPSTICK APPLICATOR

Herman Begin and Abraham Gold, Bronx, and
Herman Gold, Flushing, N. Y., assignors to Gold
Bros., Inc., New York, N. Y.

Application June 30, 1947, Serial No. 753,008

7 Claims. (Cl. 15—132.7)

1

This invention relates to new and useful improvements in a lipstick applicator of the ball-type.

The principal object of the invention is to provide a novel lipstick applicator, wherein the applicator proper is a rollably mounted ball for picking up lipstick material from a lipstick pencil therebehind and carrying the picked up material to the lips while rolling the ball over the lips.

A feature of the invention is a mounting for the ball incorporating a bezel forward of the middle plane of the ball and which not only acts as a scraper relative to the ball but also coacts with another part, also preferably incorporating a bezel, for permanently retaining the ball and permanently maintaining it freely rollable.

Another feature of the invention is a wholly removable inner barrel having a piston therein acted on by a spring also in the barrel, such spring for thrusting against the piston to resiliently forwardly urge the lipstick pencil to endwise advance against the rear side of the ball thereby always to maintain the latter embedded in the forward end of the lipstick.

A further feature is a means at the forward end of the barrel for engaging the forward end of the piston, so arranged that when the barrel is removed for insertion of a lipstick said means will ordinarily prevent the spring from ejecting the piston from the barrel, and also so arranged that when the barrel is held in the container with the rear end of the lipstick in a forward compartment in the piston the latter will be guided to a line of advance such that its forward end may pass beyond said means.

Still another feature of the invention is the provision of a piston not only having a forward compartment, but one also having a rear compartment, to establish a cup mounting for the forward end of the spring; there also being preferably present a cup mounting for the rear end of the spring, this mounting formed in a wall closing the rear end of the barrel.

Still a further feature of the invention is a permanent securement of the forward end of the spring in its cup mounting in the piston, whereby the piston and spring constitute a collection of permanently coupled parts easy to locate if ever accidentally ejected as such collection from the barrel following removal of the barrel from the container.

Another feature of the invention is a novel form of simple and reliable manually releasable latch means for securing the barrel within the container.

2

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of the lipstick container and applicator constructed in accordance with the present invention.

Fig. 2 is a perspective view thereof, with a cover cap removed.

Fig. 3 is an enlarged longitudinal sectional view taken on the line 3—3 of Fig. 1.

Fig. 4 is a transverse sectional view taken on the line 4—4 of Fig. 3.

Fig. 5 is a fragmentary perspective view, looking toward the forward end of the inner barrel.

Fig. 6 is a perspective view, showing the spring securing means carried in the piston.

Fig. 7 is a fragmentary perspective view, looking toward the rear end of the main outer casing of the container.

Fig. 8 is a fragmentary perspective view, looking toward the rear end of the inner barrel.

Fig. 9 is also a fragmentary perspective view, showing a leaf spring element of one of a pair of latches and a releasing finger-piece carried by said spring element.

Fig. 10 is an enlarged detailed view of a portion of Fig. 3.

Fig. 11 is a plan view of Fig. 10 with a portion of the sleeve broken away to reveal interior construction.

Fig. 12 is a partial longitudinal sectional view taken on the line 12—12 of Fig. 11.

Fig. 13 is a partial transverse sectional view taken on the line 13—13 of Fig. 11.

The lipstick container and applicator, according to the present invention, includes an outer casing 15 comprising a cylindrical sleeve 16 within the forward end of which is interiorly telescoped a main shell cup 17 having a conically shaped front wall. The shell cup 17 is suitably fixed in the sleeve 16, as by force fit therein, or otherwise.

The shell cup 17 at the center of its front wall has an opening 19, marginally of which the shell cup is shaped to present a bezel 20.

A spherical ball 21, made of metal or of any other suitable material, is freely rollably positioned behind the bezel 20 by an inner bezel 22 formed marginal to the opening 23 through the polygonal disc 24, suitably secured, as by the

soldering indicated at 25, to the interior of the shell cup 17.

A friction-held cap 26 is carried by the container, with the rear end of the cap abutting the front end of the sleeve 16; which two parts are of the same external diameter, so that with the cap in place the main length of the container is of smooth contour throughout.

A lipstick pencil 27 has its rear end mounted in a forward compartment of a double hollow piston 28' movable axially of an inner cylindrical barrel 28; there being an expansile coil spring 29 seated at its forward end in the rear compartment of the piston 28', and seated at its rear end in the recess 30 in an end cap 31 secured to the 10 rear end of the inner barrel 28.

The rear end of the barrel 28 is fitted tightly, and if desired is otherwise suitably permanently anchored, to the circular groove 32 cut in the forward face of the end cap 31.

Diametrically opposite sides of the cap 31 are formed with recesses each having a major subdivision 33 and a reduced minor subdivision 34. Latches are secured to the sides of the barrel 28 and each comprises a finger piece 35 disposed in the major subdivision 33 of its respective recess and a reduced neck portion 36 disposed in the minor subdivision 34 of its respective recess. The reduced neck portions 36 are formed on ends of the leaf springs 37 and the leaf springs are attached at their other ends to the sides of the barrel 28. The finger piece 35 of each latch is secured to the free end of the associated neck portion 36, and the forward end of the leaf spring 37 is welded, soldered or in any other manner secured to the sides of the inner barrel 28. The two latches extend along diametrically opposite sides of the barrel 28.

The two leaf springs 37 are resiliently biased to have their free ends spaced away from the adjacent sides of the barrel 28 so as to maintain the two finger pieces 35 normally projected to a predetermined extent from their recess subdivisions 33, as shown in Figs 3 and 10.

When the inner barrel 28 is inserted into the sleeve 16 of the outer casing 15, through the open rear end of the sleeve 16, and with the main or wider portions of the leaf springs 37 aligned with matching openings provided therefor in the rear end of the sleeve, a final slight endwise thrust on the inner barrel snaps the neck portions 36 of the leaf springs to interlock with the sleeve 16.

The matching openings of the sleeve 16 are most clearly shown in Fig. 7, where they are shown as being formed in an inturned annular flange 39 at the rear end of the sleeve 16. Each such opening has a wider subdivision 40 interrupting the inner marginal portion of the flange 39, and a narrower subdivision 41 extended centrally beyond the subdivision 40. The subdivisions 40 are of such width as to allow easy endwise passage therethrough of the main wider portion of one of the leaf springs 37, and the subdivisions 41 are of a size to receive the neck portions 36 of the leaf springs 37.

While, during insertion of the barrel 28 into the sleeve 16, the main wider portions of the leaf springs 37 are passing through the opening subdivisions 40, the leaf springs 37 are placed under tension by being compressed against the sides of the barrel 28; so that as soon as the wider portions of the leaf springs 37 have passed completely through the subdivisions 40, and the neck portions 36 of the leaf springs 37 become aligned with the opening subdivisions 41, the leaf springs

snap outward so that shoulders 42 at the inner ends of the neck portions 36 engage the material of the flange 39 on diametrically opposite sides of the subdivisions 41. The parts are so shaped and dimensioned that when this last occurs, the shoulder 43 of the end cap 31 abuts the flange 39.

The spring 29, as already stated, has a cup mounting at both ends. At its rear end, such mounting is the recess 30 in the end cap 31. The cup mounting for the forward end of the spring 29 is the rear compartment of the piston 28'.

The spring 29, moreover, is permanently coupled to the piston 28'. Referring to Figs. 3 and 6, this coupling is by way of a means incorporating a disc 44 carrying a plurality of integral prongs 46. With several end convolutions of the spring 29 placed and constricted to encircle the prongs 46, the prongs are bent over to retainingly grip the convolutions, and the disc 44 is permanently secured in the piston 28' by any suitable means, as by a force fit therein.

Due to the permanent interlock between the piston 28' and the forward end of the spring 29, these parts form a sub-assembly such that accidental loss of either spring or piston is almost an impossibility, even in the case where, following removal of the inner barrel 28 from the casing 15, as for insertion of a replacement lipstick, the piston 28' is accidentally ejected from the barrel by thrust from the spring 29; although ordinarily such ejection will be prevented by means now to be described.

Said means is a straight edged inturned flange portion 45 at the forward end of the barrel 28, for engaging a forward edge portion of the piston 28'. As earlier mentioned, this arrangement will ordinarily prevent the spring 29 from ejecting the piston 28' from the barrel 28.

While we have illustrated and described the preferred embodiment of my invention, it is to be understood that we do not limit ourselves to the precise construction herein disclosed and the right is reserved to all changes and modifications coming within the scope of the invention as defined in the appended claims.

Having thus described our invention, what we claim as new, and desire to secure by United States Letters Patent is:

1. In a lipstick applicator having a tubular sleeve open at one end and closed at its other end by a shell cup rotatably supporting a ball applicator to engage one end of a lipstick, means for urging the end of the lipstick continuously against the ball applicator, comprising a tubular barrel having one end slidably inserted into the open end of the sleeve, a cap closing the outer end of said barrel, a piston slidably mounted in said barrel, the lipstick being adapted to have its end opposed to the end which engages the ball applicator extended into the inner end of said barrel and connected with the adjacent end of said piston, an expansile coil spring having one end nested in said cap, and means securing the opposite end of said coil spring to the end of said piston opposite the end adapted to be engaged by the end of the lipstick, said securing means comprising a disc secured in position within a hollow formed in the end of said piston engaged by said spring, and a pair of opposed prongs stamped from the material of said disc and beneath which several convolutions of the adjacent end of said coil spring are clamped.
2. In a lipstick applicator having a tubular sleeve open at one end and closed at its other end

75

by a shell cup rotatably supporting a ball applicator to engage one end of a lipstick, means for urging the end of the lipstick continuously against the ball applicator, comprising a tubular barrel having one end slidably inserted into the open end of the sleeve, a cap closing the outer end of said barrel, a piston slidably mounted in said barrel, the lipstick being adapted to have its end opposed to the end which engages the ball applicator extended into the inner end of said barrel and connected with the adjacent end of said piston, an expansile coil spring having one end nested in said cap, and means securing the opposite end of said coil spring to the end of said piston opposite the end adapted to be engaged by the end of the lipstick, and manually releasable latch means locking said barrel in position within the sleeve following endwise insertion of the barrel into the open end of the sleeve.

3. In a lipstick applicator having a tubular sleeve open at one end and closed at its other end by a shell cup rotatably supporting a ball applicator to engage one end of a lipstick, means for urging the end of the lipstick continuously against the ball applicator, comprising a tubular barrel having one end slidably inserted into the open end of the sleeve, a cap closing the outer end of said barrel, a piston slidably mounted in said barrel, the lipstick being adapted to have its end opposed to the end which engages the ball applicator extended into the inner end of said barrel and connected with the adjacent end of said piston, an expansile coil spring having one end nested in said cap, and means securing the opposite end of said coil spring to the end of said piston opposite the end adapted to be engaged by the end of the lipstick, and manually releasable latch means locking said barrel in position within the sleeve following endwise insertion of the barrel into the open end of the sleeve, said latch means comprises leaf springs having ends secured to the sides of said barrel and free ends releasably engageable with complementary openings formed at the open end of said sleeve.

4. In a lipstick applicator having a tubular sleeve open at one end and closed at its other end by a shell cup rotatably supporting a ball applicator to engage one end of a lipstick, means for urging the end of the lipstick continuously against the ball applicator, comprising a tubular barrel having one end slidably inserted into the open end of the sleeve, a cap closing the outer end of said barrel, a piston slidably mounted in said barrel, the lipstick being adapted to have its end opposed to the end which engages the ball applicator extended into the inner end of said barrel and connected with the adjacent end of said piston, an expansile coil spring having one end nested in said cap, and means securing the opposite end of said coil spring to the end of said piston opposite the end adapted to be engaged by the end of the lipstick, and manually releasable latch means locking said barrel in position within the sleeve following endwise insertion of the barrel into the open end of the sleeve, said latch means comprises leaf springs having ends secured to the sides of said barrel and free ends releasably engageable with complementary openings formed at the open end of said sleeve, and finger pieces carried by the ends of said leaf springs by which said springs may be disengaged from said openings freeing said barrel to be withdrawn from the sleeve.

5. In a lipstick applicator having a tubular sleeve open at one end and closed at its other end

by a shell cup rotatably supporting a ball applicator to engage one end of a lipstick, means for urging the end of the lipstick continuously against the ball applicator, comprising a tubular barrel having one end slidably inserted into the open end of the sleeve, a cap closing the outer end of said barrel, a piston slidably mounted in said barrel, the lipstick being adapted to have its end opposed to the end which engages the ball applicator extended into the inner end of said barrel and connected with the adjacent end of said piston, an expansile coil spring having one end nested in said cap, and means securing the opposite end of said coil spring to the end of said piston opposite the end adapted to be engaged by the end of the lipstick, and manually releasable latch means locking said barrel in position within the sleeve following endwise insertion of the barrel into the open end of the sleeve, the sleeve being formed at its open end with an inwardly directed flange, said flange being formed at diametrically opposite sides with openings having wide subdivisions opening to the inner periphery of said flange and narrower subdivisions extended outward from the wide subdivisions, leaf springs secured at one of their ends to diametrically opposite sides of said barrel with their free ends extended longitudinally of said barrel and toward said cap, reduced neck portions formed on the free ends of said leaf springs and projected through the narrower subdivisions of said openings so that shoulders on said leaf springs at the

35 of said narrower subdivisions securing said barrel in position in the sleeve, and means for pressing said leaf springs against the sides of said barrel to disengage said neck portions from said narrower subdivisions and to align said leaf springs with said wide subdivisions freeing said barrel to be withdrawn from the sleeve.

6. In a lipstick applicator having a tubular sleeve open at one end and closed at its other end by a shell cup rotatably supporting a ball applicator to engage one end of a lipstick, means for urging the end of the lipstick continuously against the ball applicator, comprising a tubular barrel having one end slidably inserted into the open end of the sleeve, a cap closing the outer end of said barrel, a piston slidably mounted in said barrel, the lipstick being adapted to have its end opposed to the end which engages the ball applicator extended into the inner end of said barrel and connected with the adjacent end of said piston, an expansile coil spring having one end nested in said cap, and means securing the opposite end of said coil spring to the end of said piston opposite the end adapted to be engaged by the end of the lipstick, and manually releasable latch means locking said barrel in position within the sleeve following endwise insertion of the barrel into the open end of the sleeve, the sleeve being formed at its open end with an inwardly directed flange, said flange being formed at diametrically opposite sides with openings having wide subdivisions opening to the inner periphery of said flange and narrower subdivisions extended outward from the wide subdivisions, leaf springs secured at one of their ends to diametrically opposite sides of said barrel with their free ends extended longitudinally of said barrel and toward said cap, reduced neck portions formed on the free ends of said leaf springs and projected through the narrower subdivisions of said openings so that shoulders on said leaf springs at the

inner ends of said neck portions engage the material of said flange on diametrically opposite sides of said narrower subdivisions securing said barrel in position in the sleeve, and means for pressing said leaf springs against the sides of said barrel to disengage said neck portions from said narrower subdivisions and to align said leaf springs with said wide subdivisions freeing said barrel to be withdrawn from the sleeve, said cap having its peripheral edges extended beyond the periphery of said barrel and formed on diametrically opposite sides with recesses aligned with said leaf springs, each of said recesses comprising a major subdivision and a narrower minor subdivision directed toward said leaf springs, said neck portions of said leaf springs having their free ends projected through said minor subdivisions and extended into said major subdivisions, and finger pieces mounted on said neck portions within said major subdivisions of said recess forming the means for pressing said leaf springs.

7. In a lipstick applicator having a tubular sleeve open at one end and closed at its other end by a shell cup rotatably supporting a ball applicator to engage one end of a lipstick, means for urging the end of the lipstick continuously against the ball applicator, comprising a tubular barrel having one end slidably inserted into the open end of the sleeve, a cap closing the outer end of said barrel, a piston slidably mounted in said barrel, the lipstick being adapted to have its end opposed to the end which engages the ball applicator extended into the inner end of said barrel and connected with the adjacent end of said piston, an expansile coil spring having one end nested in said cap, and means securing the opposite end of said coil spring to the end of said piston opposite the end adapted to be engaged by the end of the lipstick, and manually releasable latch means locking said barrel in position within the sleeve following endwise insertion of the barrel into the open end of the sleeve, the sleeve being formed at its open end with an in-

wardly directed flange, said flange being formed at diametrically opposite sides with openings having wide subdivisions opening to the inner periphery of said flange and narrower subdivisions extended outward from the wide subdivisions, leaf springs secured at one of their ends to diametrically opposite sides of said barrel with their free ends extended longitudinally of said barrel and toward said cap, reduced neck portions formed on the free ends of said leaf springs and projected through the narrower subdivisions of said openings so that shoulders on said leaf springs at the inner ends of said neck portions engage the material of said flange on diametrically opposite sides of said narrower subdivisions securing said barrel in position in the sleeve, and means for pressing said leaf springs against the sides of said barrel to disengage said neck portions from said narrower subdivisions and to align said leaf springs with said wide subdivisions freeing said barrel to be withdrawn from the sleeve, said means for pressing said leaf springs comprising finger pieces mounted on the free ends of said neck portions.
